UNITED STATES PATENT OFFICE.

DANIEL HUGHES, OF ROCHESTER, NEW YORK.

IMPROVEMENT IN LAMPS.

Specification forming part of Letters Patent No. 33,945, dated December 17, 1861.

To all whom it may concern:

Be it known that I, DANIEL HUGHES, of the city of Rochester, in the county of Monroe and State of New York, have invented a certain new and useful Improvement in Lamps; and I do hereby declare the following to be a full, clear, and exact description thereof, reference being had to the accompanying drawings, and to the letters and marks thereon, which drawings form part of this specification and show my invention applied to a lamp for burning kerosene or coal oil.

Of the drawings, Figure 1 is a front view or elevation of a lamp having my improvement; Fig. 2, a view also an elevation, the globe-shade and conductor having been removed; and Fig. 3 is a view by vertical section showing the air-spaces.

It has been found to be almost impossible to so construct a lamp for the use of coal-oil that a bright and large flame could be obtained without the lamp's smoking. In the efforts to correct this evil very generally inventors have resorted to such construction of the lamp as would allow of very free and full circulation of air, using as a part of the means the straight or elevated chimney-glass. A rapid circulation of air about the flame necessarily produces rapid consumption of the oil or burning-fluid, and lessens the economy of the lamp, while the chimney-glass is very liable to be broken, particularly in hand-lamps.

Now, while my invention has for its object the full supplying of air to the flame and the use of a shade, it provides for a checked or controlled circulation of air, and thus the oil is used economically and a bright and full flame obtained.

In carrying out my invention I use, as is shown by the drawings, a lamp the upper portion or body of which is a section of a cone. Around this cone-shaped part I place, usually,

one conductor C, and sometimes a second conductor B, which conductors are of conical shape, the exterior one, or that marked C, extending a short distance above the wick or wick-tube. As will be perceived, there is thus formed an air chamber or reservoir between the body proper of the lamp and the conductor or shell C. The bottom part of the conductor C has holes which are covered with wire-gauze or may have small perforations, and upon the top part of the conductor is placed the globe-shade D. The perforations or gauzed holes in the lower part of the conductor will allow of the passage of an ample supply of air, but will prevent its passing in too rapidly or in too large a current. The air thus passed in will become somewhat retarded and compressed in the air-chamber above named, where it will also become heated, and while it will fully supply the flame it will not produce that rapid movement which would occur if the track or channel for the air was regular and uniform throughout. By using the globe-glass in connection with such air-chamber and air-inlet aid is given to the chamber in the performance of its functions, the flame is protected, and a shade is used which is neither liable to be easily broken nor by its height to increase the velocity of the passage of the air by the flame.

What I claim as new, and desire to secure by Letters Patent, is—

The air-chamber between the conductor and the body of the lamp, as herein recited, the gauze-covered holes or small perforations as the inlets for the air, and the globe-shade, as they are arranged in relation to each other, and for the purposes herein set forth.

DANIEL HUGHES.
